United States Patent Office.

JOHN SEEGER AND JOSEPH SEEGER, OF WEST TROY,
NEW YORK.

Letters Patent No. 89,892, dated May 11, 1869.

IMPROVEMENT IN PUMPS.

The Schedule referred to in these Letters Patent and making part of the same.

To all whom it may concern:

Be it known that we, JOHN SEEGER and JOSEPH SEEGER, of the town of West Troy, Albany county, New York, have invented certain new and useful Improvements in Pumps for Liquids, whereby several kinds of liquids can be drawn, without mixing, and the unused part returned whence it was drawn; and we do hereby declare that the following is a full, clear, and exact description thereof, reference being had to the accompanying drawings, forming a part of this specification, and the letters of reference marked thereon, in which—

Figure 1 represents a perspective view of pump.

Figure 2, a perpendicular section.

Figure 3 is a vertical view from under side.

Figures 4 and 5 are vertical views of revolving bottom, with valves from top.

Figure 6 is a cross-section through revolving bottom and its bed, showing manner of packing.

Figures 7 and 8 are cross-sections of the same, showing the action of the valves.

The nature of our invention consists of so constructing a pump, for liquids, that the said pump will draw from the contents of several separate and distinct vessels, through as many pipes, or tubes, connecting with one common chamber, through one valve, and discharging the said liquids through one and the same duct, or nozzle, and also, at the will of the operator, return the unused, or undischarged liquid into the same vessel whence it was drawn.

The chamber of the pump is constructed as usual, and the piston, or plunger, is made solid, and properly connected with its lifting-rod, or bars and lever-handle.

A revolving chamber-bottom, provided with a single valve, is set in a fixed bed.

The said revolving bottom is packed with leather, on its under side, and filled with tallow, so as to properly fit the top of the fixed bed in which it sets.

The valve of the revolving bottom is free to move in a horizontal direction, and is provided with a bevelled projection on its under side, by which the valve is raised when the bottom is turned.

The fixed bed in which the revolving bottom works is pierced with several holes, to receive as many pipes, or tubes, through which the liquids are to be drawn.

These pipe-holes are so placed as to permit the projections of the valves entering them, when required, when the valve closes, and when the revolving bottom is turned, the projection rises up from those holes, and lifts the valve.

A shaft, connecting with and secured to the revolving bottom, passes down through the fixed bed below it. And to the said shaft, fixed below, is a mitre-gear.

The said mitre-gear is worked by another mitre-gear, fixed to a shaft, which is passed through the outer shell of the base of the pump.

To the outside of the base of the pump is attached a dial-plate, laid off with lines radiating from the centre.

The said lines are numbered 1, 2, &c., in number corresponding with the number of pipes connected with the fixed bed.

Shorter lines are also drawn to near the index-numbered lines.

The shaft connecting with the second mitre-gear, after passing through the shell of the base, also passes through the dial-plate, and is provided with a thumb-piece, by which it may be revolved.

One side of the thumb-piece is provided with a pointer, which is turned to near the face of the dial, and when moved over to one of the numbered lines, the pump, when worked, will draw from a pipe corresponding with such a numbered line, and when the pointer is moved a little distance along, over the short line, the valve will be raised, and the undischarged liquid will be returned to the vessel whence it was drawn, through the same pipe.

The duct, through which the liquids are to be discharged from the pump-chamber, is provided with a stopper, which stopper is furnished with a shaft, or steadiment, coiled with a spring, and can be thrown against the inner discharge-hole of the duct by an eccentric, made in the shaft of a thumb-piece, placed near the extreme end of the duct-holder.

The discharge-spout, or nozzle, connects with the main duct, at the top of its shell, and turns down below its lower surface-line.

A vent, provided with a float, is placed over, and connects with the duct-chamber, which, while it prevents the escape of the liquid therefrom, will also admit air, to force out whatever liquid might possibly be in the nozzle after the operation of the pump has ceased.

To enable others skilled in the art to make and use our invention, we will proceed to describe it, in reference to the accompanying drawings, and the letters of reference marked thereon, the same letters indicating like parts.

A, figs. 1 and 2, represents the chamber of a pump.

B is the plunger, suitably packed, and connected with the handle, C, by means of the connecting-bars a a, and is kept steady by the piston-rod, b.

D, figs. 2, 4, 5, and 6, represents the revolving chamber-bottom, which is provided with a valve, V, figs. 2, 4, and 7.

The said valve V is provided with a projection, c, placed on its under side, as shown in fig. 7.

A holding-bar, d, figs. 4 and 7, keeps the valve from rising out of its recess, e.

Two parts, f f, are also provided on each side of the valve V, and connect with the recess e.

This revolving bottom D is packed with leather, g, as shown in fig. 6, and secured to the bottom by the dovetail lips, impinging and holding down on the bevel

edges of the said leather, *g*, which is well saturated, on its under side, with tallow.

E, figs. 4, 6, and 7, is the fixed bed, in which works the revolving bottom *D*.

This fixed bed is pierced with several holes, as shown in fig. 3, and by the dotted lines in figs. 4 and 5.

These holes are to receive the pipes, or tubes, *h h*, figs. 6, 7, and 8.

The said pipes connect with the vessels below, which are to hold several kinds of liquids.

The revolving bottom *D* is connected with a shaft, *i*, figs. 2, 6, 7, and 8.

The said shaft *i* passes through the fixed bed *E*, and is attached to a mitre-gear, *k*, and is steadied by the bar *l*, fig. 3, at the base of the pump.

A second mitre-gear, *m*, attached to the shaft *n*, passes through the shell of the base, and through the dial-face, *o*, figs. 1 and 3, and shown by red lines in fig. 2, and is provided with a thumb-piece, *p*, by which it may be worked.

The face of the said dial *o* is marked off with the lines 1, 2, 3, and numbered thus, with numbers corresponding with such lines.

The said lines, and the numbers marked thereon, are to correspond with the number of pipes, or tubes *h*, which may be connected with the fixed bed *E*.

Shorter lines, *r*, are made near the numbered lines 1, 2, and 3.

The numbered lines indicate when the valve *V* is directly over any one of the corresponding pipes *h*, when the pointer *s*, of the thumb-piece *p*, is made to cover such a numbered line; and when the said pointer *s* is moved so as to cover a short line, *r*, it indicates that the valve *V*, shown by dotted lines in fig. 7, has passed over the pipe-hole *h* a little, enough to just raise the said valve up, but not entirely from over the said pipe-hole *h*.

When the valve *V* is directly over the pipe *h*, the pump will draw from such pipe only; and when the valve is passed a little to one side, so that its projection *c* is just passed out the opening, the liquid, if any, will pass back through the same pipe, into the vessel whence it was drawn.

The duct *t*, figs. 1 and 2; is provided with a chamber, *G*.

In this chamber works a stopper, *u*, furnished with a shaft, *u'*, which is coiled with a spring.

An eccentric, *W*, worked by the thumb-piece *W'*, impinges the end of the stopper-shaft *u'*, and throws it forward, so as to close the hole *x*, communicating with the chamber *G*, of the duct, and chamber *A*, of the pump.

When the thumb-piece *W'* is turned so as to stand perpendicular, the stopper is from the opening *x*, and when turned horizontal, the stopper is thrown against the said hole.

A nozzle, or spout, *y*, leads from the duct-chamber *G*, for the discharge of the liquids.

A vent, *Z*, is also provided close to the shell of the chamber *A*; and communicates with the duct-chamber *G*.

This vent is provided with a float, *Z'*, which prevents the escape of the liquids in that direction, and at the same time admits air, to drive out what liquid may be in the nozzle *y*.

The mode of operating this pump is as follows:

The thumb-piece *p*, figs. 1 and 3, is turned until the pointer *s* comes over one of the numbered lines, say

line 2. The turning of the said thumb-piece *p* moves the mitre-gear *m*, which works the mitre-gear *k*, attached to the shaft *i*, and connected with the revolving bottom *D*, which is worked thereby, and turns round until the valve *V* is directly over the pipe which corresponds with the numbered line 2, covered by the pointer *s*.

The hand-lever *C* is now operated, in the usual manner, and the liquid is drawn up through the valve *V*, which rises up by force of the suction, and admits the said liquid into the chamber *A*, above, when it is forced out, through the opening *x*, into the duct-chamber *G*, and from thence, through the nozzle *y*, out.

When sufficient liquid has been drawn, the pointer *s*, of the thumb-piece *p*, is turned over to the short line *r*, and the bottom *D* is turned a little, to throw up its valve *V* above the upper surface of the fixed bed *E*, yet not from directly over the openings, or pipes *h*, when the liquid in the chamber *A* is permitted to run back into the vessels below, through the recess *e*, ports *f f*, and the pipe whence it was drawn.

When the pressure of the liquid is great, such as may arise from present-use beer, the eccentric *W* is turned by the thumb-piece *W'*, so as to stand in a horizontal position, and the stopper *u'* is thrown against the hole *x*, of the duct-chamber *G*, and when the pump is to be used again, the said stopper is permitted to have only the force of its spring, which is secured by turning the thumb-piece *W'* in a perpendicular position.

Instead of a valve *V*, as shown in figs. 4 and 7, valves may be used as shown in figs. 5 and 6. This valve is hinged, and is otherwise constructed and operated as those in figs. 4 and 7, which we prefer.

Having described our invention,

What we claim, and desire to secure by Letters Patent, is—

1. The revolving bottom *D*, furnished with the valve *V*, constructed as described, in combination with the fixed bed *E*, with one or more pipe-holes *h*, all arranged and constructed as and for the purpose specified.

2. The revolving bottom *D*, packed with the leather *g*, as shown in fig. 6, and in combination with the shaft *i*, and the mitre-gears *k* and *m*, as and for the purpose set forth and described.

3. The dial-face *o*, furnished with the numbered lines 1, 2, 3, and short lines *r*, in combination with the thumb-piece *p*, with its pointer *s* and mitre-gears *m* and *k*, all arranged and operated as and for the purpose set forth as specified.

4. The eccentric *W*, worked by its thumb-piece *W'*, in combination with the stopper *u*, as and for the purpose set forth and described.

5. The vent *Z*, provided with the float *Z'*, in combination with the chamber *G* and nozzle *y*, as and for the purpose specified.

6. A pump constructed with the chamber *A*, plunger *B*, in combination with a revolving bottom, *D*, furnished with a valve, *V*, and moving in the pierced fixed bed *E*, by means of the shafts *i* and *u'*, and the mitre-gears *k* and *m*, as and for the purpose set forth and described.
